UNITED STATES PATENT OFFICE

NELSON P. BECK, OF ROCHESTER, NEW YORK

DESIGN FOR A DECK OF PLAYING CARDS

Application filed April 26, 1932. Serial No. 43,619. Term of patent 3½ years.

To all whom it may concern:

Be it known that I, NELSON P. BECK, a citizen of the United States, residing at Rochester, in the county of Monroe and State of New York, have invented a new, original, and ornamental Design for a Deck of Playing Cards, of which the following is a specification, reference being had to the accompanying drawing, forming part thereof.

The figure of the drawing is a plan view of a portion of a deck of cards showing my new design.

In the figure of the drawing is illustrated the ace, king, queen, jack and ten of the diamond suit. The other cards of the diamond suit are the same as the ten of diamonds with the exception of the change of the numeral, the nine of diamonds bearing the numeral 9 in place of the numeral ten, shown in the drawing, and the remaining cards of the diamond suit differing in the same man-

ner only as to the numeral indicating the value of the card.

The figure of the drawing also shows the ace of spades, the ace of hearts and the ace of clubs. The remaining cards of these three suits will bear the same design as the cards of the diamond suit with the exception of a spade being shown in the place of the diamond in the spade suit, and a heart in the heart suit, and a club in the club suit.

The figure of the drawing also illustrates the design of the joker, the deck of cards with the joker being fifty three, similar to the number of the cards of an ordinary deck of playing cards.

I claim:

The ornamental design for a deck of playing cards, substantially as shown and described.

NELSON P. BECK.
